AUTOMOBILE BUMPER GUARD

Henry T. King, Detroit, Mich., assignor to
Chrysler Corporation, Highland Park, Mich., a
corporation of Delaware

Application August 7, 1951, Serial No. 16,191

Term of patent 7 years

(Cl. D14—6)

To all whom it may concern:

Be it known that I, Henry T. King, a citizen of the United States, residing in the city of Detroit, county of Wayne, and State of Michigan, have invented a new, original, and ornamental Design for an Automobile Bumper Guard, of which the following is a specification, reference being had to the accompanying drawing, forming part thereof, in which:

Fig. 1 is a front elevational view of an automobile bumper guard showing my new design;

Fig. 2 is a top plan view thereof;

Fig. 3 is a side elevational view thereof;

Fig. 4 is an elevational view showing the side opposite to Fig. 3; and

Figs. 5, 6 and 7 are sections taken on the lines 5—5, 6—6 and 7—7 respectively of Fig. 1.

I claim:

The ornamental design for an automobile bumper guard, substantially as shown.

HENRY T. KING.
